US00D725868S

(12) **United States Design Patent**
Kimura et al.

(10) **Patent No.:** US D725,868 S
(45) **Date of Patent:** ** Apr. 7, 2015

(54) **MACARONI**

(71) Applicant: **Nissin Foods Inc.**, Tokyo (JP)

(72) Inventors: **Ryusuke Kimura**, Tokyo (JP); **Fusaki Kajio**, Tokyo (JP)

(73) Assignee: **Nissin Foods Inc.**, Tokyo (JP)

(**) Term: **14 Years**

(21) Appl. No.: **29/488,925**

(22) Filed: **Apr. 24, 2014**

Related U.S. Application Data

(62) Division of application No. 29/445,131, filed on Feb. 7, 2013, now Pat. No. Des. 707,419.

(51) **LOC (10) Cl.** 01-01

(52) **U.S. Cl.** **D1/126**
USPC **D1/126**

(58) **Field of Classification Search**

USPC D1/100-130, 199; 426/5, 76, 87, 92, 426/94, 95, 99, 101, 103, 104, 108, 134, 426/138-139, 143, 144, 279, 282, 283, 391, 426/514, 549, 559, 560, 660, 808; D9/439; 521/50; 251/364; 220/574; D8/83; D21/487

(57) **CLAIM**

The ornamental design for a macaroni, as shown and described.

DESCRIPTION

FIG. 1 is a perspective view of a macaroni according to Embodiment 1;

FIG. 2 is a front view of the macaroni according to Embodiment 1;

FIG. 3 is a rear view of the macaroni according to Embodiment 1;

FIG. 4 is a right side view of the macaroni according to Embodiment 1;

FIG. 5 is a left side view of the macaroni according to Embodiment 1;

FIG. 6 is a top plan view of the macaroni according to Embodiment 1;

FIG. 7 is a bottom plan view of the macaroni according to Embodiment 1;

FIG. 8 is a perspective view of a macaroni according to Embodiment 2;

FIG. 9 is a front view of the macaroni according to Embodiment 2;

FIG. 10 is a rear view of the macaroni according to Embodiment 2;

FIG. 11 is a right side view of the macaroni according to Embodiment 2;

FIG. 12 is a left side view of the macaroni according to Embodiment 2;

FIG. 13 is a top plan view of the macaroni according to Embodiment 2; and,

FIG. 14 is a bottom plan view of the macaroni according to Embodiment 2.
